John Clark Brown, Upper Montclair, N. J.

Application July 31, 1947, Serial No. 140,639

Term of patent 14 years

(Cl. D33—8)

To all whom it may concern:

Be it known that I, John Clark Brown, a citizen of the United States, residing in Upper Montclair, in the county of Essex, in the State of New Jersey, have invented a new, original, and ornamental Design for a Hook, Hanger or Similar Article, of which the following is a specification, reference being had to the accompanying drawings, forming a part thereof.

Figure 1 is a perspective view of a hook or hanger, embodying my new design; and

I claim:

The ornamental design for a hook, hanger or similar article, substantially as shown.

JOHN CLARK BROWN.
